A. J. HEITZ

ELECTROMAGNETIC SWITCH

Filed March 26, 1924

Fig. 1.

UNITED STATES PATENT OFFICE.

ALBERT J. HEITZ, OF VINCENNES, INDIANA.

ELECTROMAGNETIC SWITCH.

Application filed March 26, 1924. Serial No. 702,074.

To all whom it may concern:

Be it known that I, ALBERT J. HEITZ, a citizen of the United States, residing at Vincennes, in the county of Knox and State of Indiana, have invented certain new and useful Improvements in Electromagnetic Switches, of which the following is a specification.

This invention relates to an electro-magnetic switch for an electric lamp fixture, more particularly to a switch employed in connection with lamps in multiple for use in stores, banking rooms, offices, etc., but it is to be understood that an electro-magnetic switch in accordance with this invention can be employed for any purposes for which it is found applicable, and the invention has for its object to provide, in a manner as hereinafter set forth, a fixture of the class referred to, having means whereby one of the lamps of the multiple will be active at all times for the purpose of illuminating the interior of a store room, banking room, etc., sufficiently to enable a pedestrian, policeman or watchman to view the interior thereof at all times to discover the presence of a surreptitious or unauthorized person, fire, leakage of steam and water pipes, or when the appearance of such interior is not normal which would cause the observer to conclude that something is wrong.

A further object of the invention is to provide, in a manner as hereinafter set forth, an electro-magnetic switch for use in connection with two or more lamps and including an automatically operable lighting circuit directing means provided for the initial lighting of one of the lamps only, but will automatically operate to cut into the circuit of a second lamp in the event of the burning out of the active lamp, whereby there is obtained a continuous lighting of an interior with an aggregate of assurance and certainty.

Further objects of the invention are to provide, in a manner as hereinafter set forth, an electro-magnetic switch for the purpose referred to, which is simple in its construction and arrangement, strong, durable, thoroughly efficient in its use, readily installed, conveniently assembled, and comparatively inexpensive to manufacture.

With the foregoing and other objects in view, the invention consists of the novel construction, combination and arrangement of

parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a vertical sectional view of an electro-magnetic switch in accordance with this invention.

Figure 2 is a section on line 2—2, Figure 1, looking in the direction of the arrows.

Figure 3 is a fragmentary view in section.

Figure 4 is a section on line 4—4, Figure 3.

Figure 5 is a perspective view of the yoke forming an element of the lighting circuit controlling or directing device.

Figure 6 is a vertical sectional view of a modified form of fixture.

Figure 7 is a fragmentary view, in section, of a modification.

In each of the forms illustrated, the lighting circuit controlling or directing device employed is of the same construction, and such device includes a magnet 1 extended into and fixedly secured to a horizontally disposed metallic yoke consisting of a top bar 2, a bottom bar 3 and an end bar 4. Preferably, the bars 2, 3 are of greater length than the bar 4, and the latter intermediate its ends is formed with an opening 5. The bar 2, as well as the bar 3, is bifurcated at one end, whereby each of said bars has such end formed with a pair of furcations 6, 7. The bar 4, at each end, is formed with a tongue 8, which snugly engages between the furcations 6 and 7 of a bar 2 or 3. The outer face of the bar 4 is flush with the edge at the bifurcated end of each of the bars 2 or 3. The bar 3, intermediate its ends, is formed with an opening 9, having a threaded wall, and the bar 3, intermediate its ends, is provided with a counter-sunk opening 9, having its wall smooth throughout. The bar 2, as well as the bar 3, at the end thereof opposite its bifurcated end, is provided with an opening 11.

The magnet 1 is seated between the bars 2, 3, and is spaced a substantial distance from the bar 4. Each end of the core 12 of the magnet 1 is reduced, as at 13, and extended through an opening 11 and is fur-

thermore swaged against the outer face of a bar 2 or 3, as at 14, whereby the magnet is fixedly secured to the bars 2, 3. The reduced ends 13 of the core snugly engage the openings 11 and by connecting a magnet 1 to the yoke in the manner as stated it overcomes the necessity of threading the walls of the openings 11 and the employment of screws for securing the magnet in position with respect to the yoke.

The wall of the opening 5, in the bar 4, is threaded, and threadedly engaging with said wall is the threaded end terminal portion 15 of a pivot 16 provided with a head 18. The pivot 16 projects towards the magnet and has loosely mounted thereon a rectangular armature 19, which associates with the magnet. The head 18 of the pivot 16 is countersunk in the armature 19, as at 20, whereby the armature 19 is retained on the pivot 16.

Surrounding the pivot 16 is a flat spiral spring 21, having one end thereof, as at 22, connected to the pivot 16 and its other end as at 23 connected to the armature 19. The spring 21 is arranged against that face of the armature 19 which opposes the bar 4. The function of the spring 21 is to shift the armature 19 from vertical position. The armature 19 is moved to vertical position when the magnet 1 is energized. When the magnet 1 is de-energized, the spring 21 acting on the armature 19 will cause the latter to assume the position shown in Figure 4, 35 for a purpose to be presently referred to.

Referring to Figures 1 and 2 of the drawings, the fixture includes a base 24 of insulation, provided with an extension 25 constituting a plug. Connected to the edge of the base 24 is a casing or dome which has its body portion corresponding in contour to the contour of the base 24, and as shown by way of example the body portion 26 of the casing or dome is rectangular in contour. The body portion 26 projects from the base 24 and the height thereof is materially greater than the height of said base. The body portion 26 is formed with an outwardly extending continuous flange 27 which terminates in an integral closure 28 for said body portion 26, and the said closure 28 is of greater length and of greater width than the length and width of the body portion and further is offset with respect to the latter. The closure 28 is of the same material as the body portion 26 and is formed with a pair of oppositely extending inclined portions 29, 30. The portion 29 has an opening 31, and the portion 30 is formed with an opening 32.

Secured to the portion 29, as well as extending through the opening 31, is a bushing 33 of insulation, and secured to the portion 30 as well as extending through the opening 32 is a bushing of insulation 34.

The bushing 33 is of a different color with respect to the bushing 34, and the color of the bushing 33 is such as to indicate that it associates with the initially lighted lamp and by reference to such bushing one can tell if the lamp with which the bushing is associated is active, that it is the initially lighted lamp.

The wall of the opening formed in the bushing 33 is threaded and engaging therewith and extending into the body portion 26 is a threaded metallic shell 35, having a circuit wire connection 36 attached to the inner end thereof, and said connection 36 extends into the plug 25 and has electrical contact with a threaded shell 37, mounted on the plug 25 and formed with an inwardly extending annular flange 38. The shell 35 receives the socket 39 of the initially lighted lamp 40, and as the bushing 33 is disposed at an inclination with respect to the body portion 26, the shell 35 will extend in a like manner and the lamp 40 will be disposed at an inclination.

The bushing 34 has the wall of its opening threaded and engaging therewith is a metallic shell 41 which extends into the body portion 26 and has electrically attached to its inner end a circuit wire connection 37' which is also electrically connected to the shell 37. The shell 41 provides means for connecting the socket 42 of a lamp 43 of the multiple with the casing, and the lamp 43 is disposed at an opposite inclination with respect to the lamp 40.

The yoke to which the magnet is attached is fixedly secured against the base 24 through the medium of a contact element consisting of a substantially elongated stem 44, having its outer end provided with a flat head 45 and its inner end threaded, as at 46, which engages with the threaded wall of the opening 9 in the bar 2 of the yoke. The stem 44 extends axially of the plug 25 and base 24, and the head 45 abuts against the outer end of the plug 25.

Extending through the opening 10 in the bar 3, is a bolt 46', having its head countersunk in the inner end of said opening 7. The bolt 46' projects a sufficient distance from the bar 3 and is inclosed throughout by a sleeve 47 of insulation. Mounted on the sleeve 47, exteriorly of the bar 3, are insulated disks 48, 49 and 50. The disk 48 abuts against the bar 3, and interposed between said disk 48 and disk 49 is one end of a contact member 51. Interposed between the disks 49 and 50 is one end of a contact member 52. The contact members 51, 52 extend in opposite directions with respect to each other. Mounted on the threaded end 53 of the bolt 46 is a securing nut 54 which abuts against the outer end of the sleeve 47 and the disk 50 whereby the elements 47, 48, 49, 50, 51 and 52 are clamped.

against the bar 3. The contact 51 has its free end in electrical engagement with the plug 39 of the lamp 40, and the contact 52 has its free end in electrical engagement 5 with the plug 42 of the lamp 43. The contact 52 is formed with an extension 55 arranged in the path of the armature 19 when the latter is actuated or shifted through the medium of the spring 21, whereby the armature 19 will engage the contact 55 and close the lighting circuit to the lamp 43.

The magnet 1 is electrically connected with the contact 51 by a circuit wire 56, and the magnet 1 is also electrically connected 15 with the bar 2 by a circuit wire 57.

In the form shown in Figure 6, the base and plug, casing or dome, bushings, lamp socket contacts and the manner of securing the yoke, are similar in construction 20 to that referred to in connection with Figure 1 and like reference characters are applied thereto. In Figure 6 the circuit wire connections 36 and 37' are not employed, but in lieu thereof a pair of oppositely 25 extending contact pieces 58, 59, is used and each of which is secured to the base 24 by a conducting element in the form of a stem 60 extending through the plug 25 and having threaded engagement, as at 61, 30 with a contact piece. The stem 60, at its outer end, has a head 62 electrically engaging with the flange 63 of a metallic shell 64 connected to the plug 24. Each contact piece is connected to a metallic lamp 35 socket receiving shell 65. The shells 65 are of greater length than the shells 35 and 41 and each of which is formed at its inner end with an opening 66, through which extends a contact 51 or 52. Other- 40 wise than that as stated, the construction shown in Figure 6 is the same as that shown in Figure 1.

When the lamp 41 is active, the parts are 45 in the position as shown in Figure 1 and the lighting circuit is through the stem 44, bar 2, magnet 1, circuit connection 56, contact 51, contact 67 to lamp, from lamp, plug 39, circuit connection 36, shell 37. The magnet 1 is energized and the armature 50 19 is in a vertical position as shown in dotted lines, Figure 1, when the lighting circuit is closed, as the magnet is in series with such lamp and its circuit connections. If the lighting circuit to the lamp 40 becomes open through any cause, such as the 55 breaking of the filament 68, the magnet 1 is de-energized whereby the spring 21 will shift the armature 19 to contact with the projection 55. The lighting circuit will 60 then be directed to the lamp 43 and the circuit would then be stem 44, bar 2, bar 3, pivot 16, armature 19, projection or extension 55, contact 52, contact 69 to lamp, from lamp to shell 41, circuit connection 65 37' to shell 37.

In the modification shown in Figure 7, the pivot for the armature 19, is indicated at 70, the opening in the end bar 4, at 71 and which is not threaded. The pivot 70 would have a drive or press fit, 70 and is in the form of a rivet. The bar 3 of the yoke has depending therefrom a rivet 72, in lieu of a threaded bolt, and its lower end 73 is upset to clamp the elements 48 to 50 thereon, as well as a washer 74, which 75 is interposed between the element 50 and the upset lower end 73 of the rivet 72.

Although the switch is illustrated for employment in connection with two lamps, yet it is to be understood that the number 80 of lamps can be increased, but a three lamp switch would contain two magnetic devices, four lamp switch three magnetic devices, therefore the switch can be set up with as many lamps as desired. 85

It is thought that the many advantages of a multiple electro-magnetic switch in accordance with this invention can be readily understood, and although the preferred embodiment of the invention is as illustrated and described, yet changes in the details of construction can be had which will fall within the light of the invention as claimed. 90

What I claim is:— 95

1. A switch for an electric lamp fixture comprising a metallic yoke, a magnet secured within said yoke at the open end thereof, a spring controlled armature arranged within the yoke and supported from the closed end thereof, a plurality of oppositely disposed independent contacts supported and insulated from said yoke and circuit forming connections coacting with one of said contacts for closing a circuit and energizing said magnet, and circuit forming connections coacting with another of said contacts and with said armature for closing a circuit when said magnet is de-energized. 100 105 110

2. A switch for an electric lamp fixture comprising a metallic yoke, means adapted to communicate with an electric source for securing said yoke in a stationary position, a magnet fixedly secured within the open end of the yoke, a spring controlled armature arranged within the yoke and supported from the closed end thereof, a plurality of independent contacts supported and insulated from said yoke, circuit forming connections coacting with one of said contacts for closing a circuit for energizing said magnet, and circuit forming connections coacting with another of said contacts and with said armature for closing a circuit when the magnet is de-energized. 115 120 125

3. A switch for an electric lamp fixture comprising a supporting means, a metallic yoke within said means, a magnet secured within the open end of said yoke, a spring 130

controlled armature arranged within said yoke and supported from the closed end thereof, a plurality of contacts arranged exteriorly of the yoke, means for insulating 5 said contacts from each other, means for securing said contacts and insulating means to said yoke, circuit forming means coacting with one of said contacts for energizing said magnet, and circuit forming 10 means coacting with another of said contacts and the said armature when said magnet is de-energized.

4. A switch for an electric lamp fixture comprising a supporting means, a metallic 15 yoke within said means, a magnet secured within the open end of said yoke, a spring controlled armature arranged within said yoke and supported from the closed end

thereof, a plurality of contacts arranged exteriorly of the yoke, means for insulating 20 said contacts from each other, means for securing said contacts and insulating means to said yoke, circuit forming means coacting with one of said contacts for energizing 25 said magnet, and circuit forming means coacting with another of said contacts and the said armature when said magnet is de-energized, said last mentioned contact provided with a projection extending in the path of the armature when the magnet is de-energized and the armature shifted by its controlling spring.

In testimony whereof, I affix my signature hereto.

ALBERT J. HEITZ.
